UNITED STATES PATENT OFFICE.

CHARLES R. HARTMAN, OF VINCENNES, INDIANA.

CULTIVATOR.

SPECIFICATION forming part of Letters Patent No. 404,085, dated May 28, 1889.

Application filed November 7, 1888. Serial No. 290,187. (No model.)

To all whom it may concern:

Be it known that I, CHARLES R. HARTMAN, of Vincennes, in the county of Knox and State of Indiana, have invented a new and useful Improvement in Cultivators, of which the following is a specification.

My invention is an improvement in cultivators, having for an object to provide a simple construction by which the tooth may be set to different adjustments and be firmly held in any suitable adjustment.

The invention consists in certain novel constructions and combinations of parts, as will be hereinafter described, and pointed out in the claims.

In the drawings, Figure 1 is a perspective view of my improvement. Fig. 2 is a rear edge view of same. Fig. 3 is a cross-section on line *x x*, Fig. 6. Fig. 4 is a detail view of one of the cheeks, and Fig. 5 is a detail view of the foot-piece, all of which will be described; and Fig. 6 is a section on about line *y y*, Fig. 1.

The part A represents the rear end of an ordinary cultivator-beam, to which is attached the cheeks B, the latter being pivoted by a rivet, D, to the said beam, and being arranged on opposite sides thereof, as shown. The rivet D is arranged at about the center of the cheeks, and does not operate to hold such cheeks tightly against the beam, but is loose enough to allow their lower ends to spread or expand sufficiently to permit the adjustment of the tooth-carrier E when the clamping or connecting bolt F is released or loosened.

Near their upper ends the side plates are held to the beam by a wooden or other fragile pin, G, so that in case the tooth strikes a stone, root, or other unyielding obstruction the said pin G will break, permitting the tooth to turn back. Manifestly, instead of the break-pin G, I may use any suitable automatic trip device. The foot-piece E is pivoted at or near its upper end in and between the cheek-pieces, being preferably provided with pivot-

45 studs *e*, which enter sockets or openings *e'* in the cheeks.

Below studs *e* the foot-piece has a slot, *e²*, through which the bolt F passes. Adjacent to this slot I form the foot-piece with serrations or teeth at *e³*, which engage with correspondingly-formed serrations or teeth *b* on the inner sides of the cheeks B, at the lower

end of the latter, such teeth *e³* and *b* serving, when the parts B and E are clamped tightly together, to hold the foot-piece in any desired 55 adjustment, the bolt F serving as a convenient means of drawing the cheeks tightly against the foot-piece and securing the same when so drawn. By loosening bolt F the teeth disengage, and the foot-piece may be 6c adjusted forward or back, as desired, and when set at the desired angle may be securely clamped by the bolt F and its nut.

At its lower end the foot-piece has a split socket, H, the free edges of which are connected by the bolt *h*, by which the clamp may be tightened to grip the round stem *i* of the shoe or tooth I, so that such stem may be set 65 rotarily in the socket, which construction, in connection with the forward and back adjustment of the foot-pieces, makes the device what may be termed an "every-way shovel holding and setting attachment," which may be conveniently applied to any of the ordinary beams.

75 While the construction before described will give good results, I find that better results are accomplished by the use of an expanding or spreader spring arranged to bear between the cheeks near their lower ends, to 80 cause such cheeks to spread and disengage from the serrations of the tooth-piece when the bolt F is loosened. In the construction shown the spring J is a coil-spring held in an opening, E', in the foot-piece and bearing between the cheeks, as shown in Figs. 3 and 6, the opening E' operating to retain the spring in proper position.

85 The construction is simple and inexpensive, as the several parts can be easily made of 90 malleable iron and will be found efficient and durable in use.

It will be seen that the shovel may be set at any angle or inclination or be adjusted up or down to vary the depths at which it may 95 run.

By means of the slit *h'* in the socket H, I get the largest possible surface for clamping to prevent the turning of the shovel when at work. Thus breakage of bolts and set-screws 100 by overstraining is avoided, as the ordinary tightening of the bolt *h* is sufficient to effectually hold the stem or shovel fastening, be the socket part of the foot-piece or part of the

shovel. Manifestly, instead of using the nut on bolt *h*, the opening for the bolt in one of the sections or lips of the socket might be threaded to form a screw-bearing for such 5 screw.

It will be understood that my improvement is applicable to double-shovel plows and similar implements as well as to cultivators, and I do not desire to be confined to the use of 10 such improvements on cultivators alone.

It is preferred to arrange the ratchets, as shown, at the outer ends of the cheeks, for the reason that but very little spreading of the cheeks is, because of such arrangement, required to disengage the ratchets, and the rivet 15 *D* need not be looser than it would have to be to allow the turning of the cheeks on their pivot when at work, whereas if the ratchets were at the upper end of the foot-piece, then 20 the pivot *D* would have to be a bolt and nut, so it could be loosened to spread the cheeks sufficiently to disengage the ratchets, and the nut would be a continual source of annoyance by coming off, as it would be required to 25 be but loosely drawn, and the lower pivot would necessarily have to be a bolt also. There would thus be two nuts to loosen at every change instead of one, besides the impracticability of using a bolt for the upper 30 pivot.

The spring *J* renders the change of pitch very convenient, and the foot-piece being cast with pivot, spring-seat, slot, and socket in one integral piece is no small point of advantage.

35 Having thus described my invention, what I claim as new is—

1. An improved attachment for cultivators, plows, and the like, consisting of the cheeks, the foot-piece pivoted between the said cheeks 40 and having ratchets arranged to engage, the spreader-spring operating between said cheeks, and the clamping or connecting bolt, substantially as set forth.

2. In an attachment, substantially as de-

scribed, for cultivators, plows, and the like, 45 the combination, with the cheek-plates and the foot-piece pivoted between such cheek-plates, of a spring whereby to force such cheek-plates apart, and a clamping or connecting bolt by which to hold said cheek-plates 50 against the action of the spring, all substantially as and for the purposes specified.

3. The combination of the cheeks having serrations *b*, the foot-piece pivoted between the cheeks and having serrations *e*³ and 55 opening *E'*, the spring fitted in opening *E'* and bearing between the cheeks, and the clamping or connection bolts, substantially as set forth.

4. The improved attachment herein described, comprising the cheeks *B*, having openings *e'* and serrations or teeth *b*, the foot-piece having ratchets *e*³, slot *e*², and studs *e*, and the clamping or connection bolt, 60 substantially as herein described. 65

5. In an attachment, substantially as described, the combination of the beam, the cheeks provided at their lower ends with ratchets and pivoted above such ratchets to the beam, the foot-piece pivoted above such 70 ratchets to the cheeks and provided below its pivot with ratchets, and the clamping-bolt, substantially as set forth.

6. The improved attachment herein described, consisting of the cheeks having openings *e'* and serrations *b*, the foot-piece having socket *H* at its lower end, provided near its upper end with studs *e* to enter openings *e'*, and provided below such studs with opening *E'* and with ratchets *e*³ and slot *e*², the 75 spring fitted in opening *E'* and bearing between the cheeks, and the clamping or connecting bolt, substantially as set forth. 80

CHARLES R. HARTMAN.
